RECOIL-GUN.

No. 923,051.

Specification of Letters Patent.

Patented May 25, 1909.

Application filed April 30, 1907. Serial No. 371,061.

To all whom it may concern:

Be it known that we, OTTO LAUBER and FRANZ BÖMINGHAUS, residing at Essen-on-the-Ruhr, Germany, both subjects of the 5 Emperor of Germany, have invented a certain new and useful Improvement in Recoil-Guns, of which the following is a specification.

The present invention relates to a recoil-10 gun with fluid brake in which, when the gun barrel is elevated, a part of the brake is automatically adjusted to regulate the length of recoil.

One embodiment of the invention is shown 15 in the accompanying drawings by the way of example.

Figure 1 shows those parts of a barrel recoil gun to which the invention relates, partly in side view and partly in vertical longitudinal section; Figs. 2 and 3 are sections on line 20 2-2 and 3-3, Fig. 1, looking from the left; Fig. 4 shows a part of Fig. 2 but with some parts in another position; Fig. 5 shows a part of Fig. 2 on an enlarged scale and with a 25 somewhat different construction, and Fig. 6 is a section on line 6-6, Fig. 5.

Reference will first be had to the embodiment shown in Figs. 1 to 4.

The gun-barrel A is mounted to slide on 30 the track-carrier B, which is swingingly mounted in the cradle C through the medium of horizontal trunnions which are mounted on arms b' and one of which is shown in the drawings. The cradle forming a part not 35 partaking of the elevation of the gun, is connected to the carrier B by an elevating mechanism and can, by means of a lateral training mechanism, be swung relatively to the mount D about the axis of the vertical 40 trunnion c' which is journaled in the mount.

The training and elevating mechanisms, which are not shown in the drawings, may be of any suitable construction.

The interior of the carrier B contains the 45 hydraulic brake E F and the recuperator spring G. The brake cylinder E is rigidly connected to the horn a' of the breech of the gun-barrel, while the piston rod F is rotatably but non-slidably mounted in the cap L 50 which closes the carrier B. The brake-piston consists of a piston-body H rigidly connected to the piston rod F and a rotary disk J. For the passage of the fluid from one side of the piston to the other passageways h' 55 and i' are provided in the piston body H and

in the rotary disk J. A projection i² on the disk J engages in a curved groove e' cut in the wall of the brake cylinder.

Within the carrier B a shaft K is journaled in bearings b³ on the carrier. The shaft K 60 extends parallel to the piston-rod F and is positively connected thereto by means of a pair of intermeshing toothed sectors M N (Figs. 1 and 3).

That end of the shaft K which is nearest 65 the breech of the gun-barrel is provided with an arm P which projects through a slot b⁴ in the carrier B and in one of the trunnion-arms b' and terminates in a ball-pivot p' which is journaled in one end q' of a link Q 70 which has its other end q² formed as bearing for a second ball-pivot r'. The pivot r' is located on a bolt R secured in the cradle C. The arrangement of the parts P Q R is clearly 75 shown in the drawings and particular attention is to be paid to the fact that both ball-joints (p' q' and r' q²) are eccentrically disposed relatively to the axis of the horizontal trunnions.

When the several parts of the gun assume 80 the positions shown in Figs. 1 to 3, the brake is adjusted for the longest recoil, as the passageways i' of the rotary disk J completely register with the passageways h' of the piston body H (Fig. 2).

If now the gun barrel is elevated, the arm 85 P and the link Q are carried along therewith and the link Q swings about the center of the ball-pivot r' as the cradle C does not partake of the movement of the gun-barrel. During 90 the elevating of the gun-barrel the center of the ball-pivot p' therefore moves along the arc x-x (Fig. 1) that is to say it moves toward the axis of the trunnions and this results in the arm P effecting a swinging movement in the direction of the arrow Y (Fig. 2).

During this proceeding, a small movement 95 takes place in the two ball-joints (p' q' and r' q²). The turning movement of the arm P is partaken of by the shaft K and through the 100 medium of the toothed sectors M N, by the piston rod F which, together with the piston-body H turns in the direction of the arrow Z (Fig. 2). If the gun-barrel is elevated about

50° the arm P moves to the position shown in 105 Fig. 4 in which the passageways i' are about half covered by the piston-body and the recoiling parts of the gun will therefore have come to rest when they have moved about half the way of the longest recoil.

It is evident that for each elevation between 0° and 50° a recoil corresponds which lies between the longest and that which is obtained by the adjustment of the brake shown 5 in Fig. 4.

The above-described device for automatically adjusting the brake is mainly distinguished from the known devices of this kind by being very simple and also by acting in a 10 reliable manner. It can further easily be made without play and the frictional losses are very small.

According to Figs. 5 and 6 the link, which connects the arm P with the bolt R, may consist of two parts S S' having their opposing 15 ends provided with right-hand and left-hand screw-threads and coupled together by means of a correspondingly threaded sleeve T. By turning the sleeve T the link S S' 20 can be lengthened or shortened. A spring V which is secured in the link-part S can enter into engagement with a notch t' in the sleeve T to secure the sleeve against accidental turning.

25 By means of the last-described arrangement it is possible, on assembling the brake, to adjust the shaft K in such a manner that, when the sector M is shoved on the square which is provided therefor on the shaft K, its 30 teeth fit snugly in the spaces between the teeth of the sector N, the position of which is determined by the relative position of the passageways $h' i'$. The improved arrangement therefore facilitates the assemblage of 35 the brake; it further makes it possible to compensate for small inaccuracies caused by wear or originating from the preparation of the details, which inaccuracies influence the relative position of the throttling members 40 H J. Moreover, by suitable adjustment of the length of the link and the resulting change in the relative position of the throttling members H J, it is possible to compensate for such non-uniformities in the recoil- 45 lengths which, for the same elevation, may arise from various causes, such as from condensation of the brake-fluid. Instead of the

ball-joints any other universal joint performing the same function may be used.

The invention is also adapted for guns in 50 which another part of the brake is adjustable to regulate the length of recoil.

Having now described the invention, what is claimed as new is:—

1. In a recoil gun, the combination with 55 the gun barrel and a gun part not partaking of the elevation of the gun, of a recoil brake partaking of the elevation of the gun barrel and adjustable to regulate the length of the recoil, a shaft extending longitudinally of the 60 brake and connected to the brake to adjust the same, and a link arranged between the shaft and the gun part not partaking of the elevation of the gun, said link being formed of two members adjustable relatively to each 65 other.

2. In a recoil gun, the combination with 70 the gun barrel and a gun part not partaking of the elevation of the gun, of a recoil brake partaking of the elevation of the gun barrel 75 and adjustable to regulate the length of the recoil, a shaft extending longitudinally of the brake and connected to the brake to adjust the same, and an extensible link arranged between the shaft and the gun part not partaking of the elevation of the gun.

3. In a recoil gun, the combination with a 80 gun barrel and a part not partaking of the elevation of the gun, of a recoil brake partaking of the elevation of the gun barrel and 85 adjustable to regulate the length of the recoil, and an adjustable connection between the recoil brake and the part not partaking of the elevation whereby the length of the recoil is adjusted when the gun is elevated.

The foregoing specification signed at Düsseldorf, Germany, this 22nd day of March, 1907.

OTTO LAUBER.
FRANZ BÖMINGHAUS.

In presence of—

ALFRED POHLMAYER,
PETER LIEBER.
